UNITED STATES PATENT OFFICE.

WILLIAM S. TOWNSEND AND FRANK E. DOUGLASS, OF ROCHESTER, PENNSYLVANIA.

DISPENSING AND DISPLAY PUMP.

Application filed August 28, 1922. Serial No. 584,809.

To all whom it may concern:

Be it known that we, WILLIAM S. TOWNSEND and FRANK E. DOUGLASS, citizens of the United States, residing at Rochester, in the county of Beaver and State of Pennsylvania, have invented certain new and useful Improvements in Dispensing and Display Pumps, of which the following is a specification.

Our invention relates to display means for oil dispensing pumps, as shown in our application Serial No. 567,836, filed June 12, 1922.

The object of the invention is to combine a measuring pump with a visible display means of the character shown in said application. This object is accomplished by the construction shown in the accompanying drawing, in which:

Fig. 1 is a central vertical section of our improved dispenser.

Fig. 2 is a front elevation thereof.

Fig. 3 is a side elevation showing another use of the dispenser.

Fig. 4 shows a modified form of display container.

Fig. 5 is the enlarged vertical section of the upper end of the display cylinder.

Fig. 6 shows the central guide tube partly in section.

Figs. 7, 8 and 9 are detail views of the pump-cylinder head.

Fig. 10 is a detail sectional view of the foot piece of the pump cylinder.

Figs. 11 and 12 show details of the pump-piston; and Fig. 13 is a plan of the foot piece of the pump cylinder.

Referring to the drawings, the lower or foot piece 1 of the pump cylinder 7 is of a general funnel-like form with a plurality of apertured lugs 2 at intervals around its upper wide end and the head piece 8 of the cylinder is provided around its lower edge with similar spaced lugs 9; the said foot piece 1 and head piece 8 being connected by the rods 10 which draw them securely together upon the ends of the pump cylinder. The lower or foot piece 1 is provided with an upwardly opening check valve 3, a depending threaded attaching nipple 4 squared at 5 so as to receive a wrench, by means of which the pump may be secured to the spud of a barrel, drum, stand or other support.

Depending from the foot piece 1 just

below the valve 3 is the inlet or suction pipe 15 to extend down into the barrel, cask or the like, and this pipe 15 is provided with a lower section 16 in sliding connection therewith so that it may be adjusted for barrels, etc., of varying depth. This section 16 is provided with a plain stuffing box 17 screwed into the upper end so that it may be properly adjusted and held in its adjusted position.

The foot piece 1 is further provided with an inclined inlet pipe or nipple 18 on the outer end of which is a drip pan 19 provided with a grid 20 resting on an annular series of lugs 21. A circular screen 21' is also provided so that all dust, grit and other foreign matter will be prevented from returning with the drip back to the barrel or the like. Gaskets 22 will be provided for the ends of the pump cylinder.

The head piece 8 of the pump cylinder 7 is formed as a casting provided with a closed upper end having an annular seat 23 for the lower end of the glass display cylinder 24, and with a threaded aperture 25 opening into the lower end of said display cylinder. The side of the head piece 8 has a discharge outlet 26 from which leads the upwardly inclined discharge pipe 27 provided with a depending outer end directly over the drip pan 19 and provided with a downwardly opening check valve 28; this construction forming a non-drip outlet or discharge for the pump.

The cap piece 29 for upper end of the glass display cylinder 24 is provided with a central aperture through which extends the upper threaded end 31 of a tube 30. The lower end of the tube 30 is screwed into a threaded aperture in the center of the pump cylinder head 8 and receives the upper end of the rack 32 of the pump piston 33. The toothed edge of the rack is engaged by a pinion 34, the shaft 35 of which is mounted in bearings in the head 8 with its outer end extending through a stuffing box 36. A crank 37 is secured to the outer end of the shaft 35 for rotating the pinion to raise and lower the rack and piston. The plain or rear edge of the piston rack 32 engages guide lugs 38 opposite to the pinion 34 so that the rack cannot be forced out of engagement with the pinion and will be held to travel in a straight line.

The piston 33 is formed of a disk 40 hav-

ing a central aperture for the lower end of the rack and a plurality of openings 41. On top of the disk 40 is a cup leather 42 held at its center on the rack and held yieldingly 5 therebeyond over the openings 41 by a spring 43 having a plurality of arms 44. As before stated, the central tube 30 projects through the cap piece 29 and upon a plug 46 screwed into its threaded end 31 is a nut 10 45 which forces the cap 29 and the glass cylinder 24 down towards the pump cylinder head 8. Suitable gaskets 46' are placed at the ends of the glass display cylinder.

The threaded plug 46 has a central 15 threaded bore in which is screwed a gage screw 47 which may be adjusted so as to limit the upward movement of the rack and piston and so accurately adjust the amount of oil lifted by the piston and discharged 20 through the discharge spout. Usually the screw 47 will be set so that the pump will discharge a quart of oil whenever the piston is moved to the upward limit. The plug 46 and screw 47 close the upper end of the central tube 30 so that there is no possibility of 25 any oil being discharged through the tube 30. This tube 30 not only serves as a guide tube enclosing the upper end of the rack but is also a central connecting rod to hold the 30 display cylinder in place. The cap piece 29 is provided with a manually closed vent valve 50.

In operation the pump is secured in the 35 spud or bung hole of a drum or barrel with the lower end of the suction pipe resting on the bottom of the drum or barrel and the vent 50 open. The crank is operated in one direction to raise the piston and fill the pump cylinder with oil. The movement of the 40 crank will now be reversed and the oil will pass upwardly through the piston openings and around the cup leather. On the next upstroke of the piston, the cup leather will close the piston openings and lift the oil and 45 force it up into the display cylinder 24 filling the same. The air vent 50 will now be closed and subsequent like operation of the pump will cause a measured quantity of oil to be discharged through the valved outlet 50 spout into any suitable container resting on the strainer supported on the drip pan grid. The outlet valve being self-closing shuts off and prevents dripping of the oil immediately after the upstroke of the piston has 55 been completed. The exact quantity may be determined by adjusting the screw 47.

This mechanism is designed so that the liquid being dispensed is at all times displayed in the glass container to the prospective buyer and it has the same advantages in this respect as has the display attachment in our pending application before referred to.

Referring now to Fig. 3 of the drawing, it 60 will be seen that the mechanism above de-

scribed, instead of being secured directly to a barrel or the like may be mounted on a pedestal or standard 60 comprising a cap piece 61 having a threaded aperture for the threaded nipple 4, a base 62 and a cylindrical body 63 held between the cap and base; the suction tube 15-16 extending down through the tube 60 and base 62. The lower end of this suction pipe could then be coupled to an underground storage tank, not 75 shown.

In Fig. 4 is shown a further modification with respect to the display container; there, instead of a single glass cylinder as in Fig. 1, are provided two parallel glass tubes 70-71 connected within the cap piece 72 by a curved passage 73. The lower end of tube 70 opens into the pump cylinder head 8 and the lower end of the tube 71 opens directly into the discharge nozzle 27, so that as the 80 pump piston rises it will force the oil up into the glass tube 70 and down through the tube 71.

The central tube 30 acts to guide and 85 enclose the piston rod or rack and also to connect the cap piece 72 and head 8, and also contains the same plug 46 and adjusting screw 47 for the piston rack.

The tube 30 is provided with a threaded 90 aperture 30' within the display cylinder 24, which is normally open to vent tube 30 and permits proper operation of the piston rod. Should the display cylinder 24 get broken, 95 however, a plug not shown will be screwed in to close the aperture 30' and the aperture 25 in head 8 will also be closed by a suitable plug not shown, whereupon the pump may be operated without the display feature until another display cylinder 24 may be placed in position.

Various changes may be made without departing from the spirit of my invention. In Fig. 3 it will be noticed that the drip from pan 19 will flow into the cylinder 60 from 100 which it may be withdrawn by a spigot 64.

What we claim is:-

1. A liquid dispenser comprising a measuring pump, a glass liquid display container seated at its lower end upon the upper end of the pump casing in vertical alignment therewith and communicating with the pump cylinder above its piston to be filled with liquid by the pump for display purposes, a securing cap at the upper end of said display container, and means connecting said cap with the upper end of said pump cylinder.

2. A liquid dispenser comprising a pump cylinder having a tubular guide extending up from the upper end, a piston provided with a piston rod extending up into said tubular guide, a discharge spout having a self-closing valve, a glass container seated at the lower end on top of the pump cylinder and communicating with the interior of the 115 120 125 130

cylinder, a cap at the upper end of the glass container and connected by said tubular guide to the upper end of said container to hold it in place on the pump.

- 5 3. A liquid dispenser comprising a pump cylinder, a valved inlet therefor, and a discharge spout at its upper end provided with a valve, a central vertical guide tube on the top of the cylinder, a piston having a piston rod extending up into said tube, a glass display container seated at its lower end on the top of the pump cylinder, means within the top of the pump cylinder for actuating said piston, a cap closing the upper end of said 15 glass container and secured to the upper end of the said guide tube, a manually controlled air vent in said cap; the lower end of the glass cylinder being in communication with the upper end of the pump cylinder.
- 20 4. A liquid dispenser comprising a pump cylinder, a valved inlet therefor, and a discharge spout at its upper end provided with a valve, a central vertical guide tube on the top of the cylinder, a piston having 25 a piston rod extending up into said tube, a glass display container seated at its lower end on the top of the pump cylinder, means within the top of the pump cylinder for actuating said piston, a cap closing the upper end of said 30 glass container and secured to the upper end of the said guide tube, a manually controlled air vent in said cap, the lower end of the glass cylinder being in communication with the upper end of the pump cylinder, and an adjusting screw in 35 the upper end of the guide tube operable from the exterior of said glass container to limit the upward movement of the pump piston.

- 40 5. A liquid dispenser comprising a pump cylinder, a foot piece in which the lower end of the cylinder is seated, a head piece seated on top of the cylinder, means for securing the cylinder and its head and foot 45 pieces together, an inlet nipple depending from the said foot piece, means for securing the nipple to a barrel or other support, a suction tube leading down from said nipple, an inlet check valve, a valved piston in the 50 cylinder provided with a toothed piston rod, a shaft having a pinion mounted in the cylinder head and meshing with the toothed piston rod, a guide tube extending up from the cylinder head and into which the piston rod extends, a glass display container seated at its lower end on the cylinder head and communicating with the pump cylinder, a cap closing the upper end of the glass 55 container, and secured centrally to the up-

per end of said guide tube, and a manually controlled air vent in the said cap.

6. A liquid dispenser comprising a pump cylinder, a head therefor having upper and lower annular seats, a foot piece having an annular seat for the lower end of the pump cylinder, tie rods securing the head and foot pieces together on the cylinder, the foot piece having a depending attaching nipple, an inlet check valve and the head piece having a discharge spout provided with a check 70 valve, a drip pan below the discharge spout and having a tubular connection with the interior of said attaching nipple, a glass cylinder seated at its lower end on the upper side of the pump cylinder head, said 75 head having an opening leading into the glass cylinder, a cap in which the upper end of the glass cylinder is seated, and a manually controlled air vent in the cap.

7. A liquid dispenser comprising a pump cylinder, a foot piece in which the lower end of said cylinder is seated, an attaching nipple depending from the foot piece, an inlet check valve, a head in which the upper end of the cylinder is seated, said cylinder, head 85 and foot piece being secured together, an outlet spout leading from the head and provided with an outlet check valve, a glass display container seated on top of said cylinder head and communicating with the interior thereof, a guide tube extending up from said head, a valved piston having a piston rod extending up into said guide tube, a cap secured to the upper end of the tube engaging the upper part of the glass container 95 and securing same in place on the pump cylinder head.

8. A liquid dispenser comprising a pump cylinder, a valved inlet therefor, a valved discharge spout at its upper portion and a 100 threaded plug-receiving opening in its top, a central vertical guide tube on top of the cylinder and having a threaded plug receiving vent aperture near its upper end, a glass display container mounted on the upper end 105 of the pump cylinder and having a manually controlled air vent in its top, a valved piston on the pump cylinder, a piston rod therefor extending up into said central guide tube and means for actuating the piston; 110 the threaded aperture in the guide tube and that in the cylinder head being adapted to be plugged in case the glass display cylinder should be broken.

In testimony whereof we affix our signatures.

WILLIAM S. TOWNSEND.
FRANK E. DOUGLASS.
